(57) **CLAIM**

The ornamental design for an adapter, as shown and described.

DESCRIPTION

FIG. 1 is a perspective view of an adapter showing my new design;
FIG. 2 is another perspective view thereof;
FIG. 3 is a front elevational view thereof;
FIG. 4 is a rear elevational view thereof;
FIG. 5 is a left side elevational view thereof;
FIG. 6 is a right side elevational view thereof;
FIG. 7 a top plan view thereof;
FIG. 8 a bottom plan view thereof; and,
FIG. 9 is an enlarged view of a main body of the adapter. The short dash-long dash broken lines shown in FIG. 9 define the bounds of the claimed design and form no part thereof.
